UNITED STATES PATENT OFFICE.

HENRY VAN WIE, OF SAN FRANCISCO, CALIFORNIA.

NON-REFILLABLE BOTTLE.

SPECIFICATION forming part of Letters Patent No. 721,759, dated March 3, 1903.

Application filed August 23, 1902. Serial No. 120,832. (No model.)

To all whom it may concern:

Be it known that I, HENRY VAN WIE, a citizen of the United States, residing at San Francisco, in the county of San Francisco and State 5 of California, have invented a new and useful Non-Refillable Bottle, of which the following is a specification.

My invention is an improvement in that class of devices known as "non-refillable bottles," and has for its general object to provide a device of this kind which can be readily applied to bottles of any size and shape and in which but slight change has to be made in the bottle.

15 It further consists in providing a valve-seat in the neck of the bottle and a ball-valve adapted to close the valve-opening against admission of liquid into the bottle and to open when it is desired to pour liquid from the bottle.

20 The mode of constructing my devices is fully shown in the accompanying drawings, in which—

Figure 1 is a view, partly in section, of my devices in position, the bottle being in an up-right position. Fig. 2 is a view, partly in section, showing the position when the bottle is decanted. Fig. 3 is a section on the line 3 3 of Fig. 1. Fig. 4 is a detail perspective view. Fig. 5 is a detail of the valve-seat and retaining-springs.

In employing my device the bottle A is first filled, the various parts of the device being subsequently placed in position. These devices are all adapted to be seated in the 25 neck of the bottle, the only change made in the bottle being the formation of two oppositely-disposed vertical wedge-shaped recesses A' formed in the neck of the bottle and an annular recess A² formed above said 30 wedge-shaped recesses. A cylindrical funnel-shaped valve-seat B is provided, having two exterior parallel annular shoulders B' formed on it, between which rests a suitable packing-ring B². The lower cone-shaped portion of the valve-seat has two or more apertures B³ produced in it to permit passage of the liquid. The lower end of the seat terminates in a dependent sleeve B⁴, and through the seat and sleeve passes a rod C, having at 45 its lower threaded end a weight C', and between the weight and sleeve and bearing against both is a spring C². A ball-valve D

is rigidly secured on the rod about midway its length, and at the upper end of the rod is a circular disk D'. Secured upon opposite 55 sides of the upper part of the valve-seat are upwardly and outwardly projecting springs E, said springs being adapted to fit in the recesses A'. A split ring F is adapted to be forced in the recess A².

All of the parts, excepting the part F, are placed in position relative to each other before being placed in the bottle. When the bottle has been filled, the parts named are placed in the neck of the bottle, the springs 65 E being forced inward when inserted and springing outward into the recesses A' as soon as the proper position has been reached. It would then be extremely difficult to withdraw the devices; but to make it impossible to tamper with the side springs the split ring F is forced into the position shown in the drawings, its outer edge fitting into the annular recess, and it may be cemented therein, if desired. The weight of the ball-valve, aided by 75 the spring C² and weight C', will tend to force the ball firmly in its seat. When the bottle is decanted, however, the weight will act in the opposite direction and, overcoming the spring, the ball will be forced away from the 80 valve-seat and liquid can pass through the apertures around the ball and disk and through the ring, as shown by the arrows in Fig. 2.

The disk D' serves the double purpose of preventing tampering with the ball D and also 85 serves to force same into its seat should any attempt be made to force liquid around the disk. The ring F acts as a guard to the springs E, which hold the devices from withdrawal, while the packing-ring B² holds the devices 90 firmly in the neck of the bottle. When the devices are in place, the usual cork G is placed in position.

It will thus be seen that I have a very cheap, durable, and efficient device of the kind described, and it is obvious that slight modifications can be made in my device without in any way departing from the spirit of my invention.

Having thus fully described my invention, 100 what I claim as new, and desire to secure by Letters Patent of the United States, is—

1. In a non-refillable bottle, the combination with a bottle having vertical recesses on

opposite sides of the neck, a valve-seat adapted to be secured in the neck of the bottle, springs secured to the upper portion of the seat and adapted to fit in said recesses, a ball-valve adapted to rest in said seat, and a rod passing through the ball and seat and carrying a weight at its lower end and a disk at its upper end.

2. In a non-refillable bottle, the combination with a bottle, a valve-seat in the neck of the bottle, a packing-ring between the seat and the sides of the neck, a ball adapted to

act as a valve, a rod passing through the ball and extending into the bottle, a weight on the end of the rod, a coiled spring around the rod adjacent the weight, a circular disk at the opposite end of the rod, and means to prevent withdrawal of the parts named from the neck of the bottle. 15
